UNITED STATES PATENT OFFICE

NAN BARCLAY, OF NEW YORK, N. Y.

DESIGN FOR A RING

Application filed December 20, 1930. Serial No. 38,033. Term of patent 7 years.

To all whom it may concern:

Be it known that I, NAN BARCLAY, a citizen of the United States, residing at New York, in the county of New York and State of New York, have invented a new, original, and ornamental Design for a Ring, of which the following is a specification, reference being had to the accompanying drawings, forming part thereof.

I claim:

The ornamental design for a ring as shown.

NAN BARCLAY.
